UNITED STATES PATENT OFFICE.

EDWIN CLARK, OF LANCASTER, PENNSYLVANIA.

IMPROVED ALARM AND INDICATOR FOR GRIST AND FLOURING MILLS.

Specification forming part of Letters Patent No. **34,130**, dated January 14, 1862.

To all whom it may concern:

Be it known that I, EDWIN CLARK, of the city and county of Lancaster and State of Pennsylvania, have invented a new and useful Improvement in an Alarm and Indicator for Grist, Flouring, and other Mills, to notify the attendant when the mill is running regularly or otherwise and to sound an alarm when running irregularly from any cause; and I do hereby declare that the following is a full, clear, and exact description of the construction of the same, reference being had to the accompanying drawings, making a part of this specification, in which—

Figure 1 represents in perspective the alarm and indicating apparatus connected with an ordinary grist or flouring mill. Fig. 2 represents, also in perspective, but on an enlarged scale, a modification of the governor and cam represented in Fig. 1 for working the alarm and indicator; and Fig. 3 represents a modification of the construction of the tappets that are struck by the cam or cams on the governor rod or shaft for sounding the alarm.

I am aware that a governor has been used for operating certain parts of machinery, and I do not claim a governor as such.

I am also aware that an alarm has been connected with a mill-hopper in such a manner that when the hopper becomes empty the alarm will be sounded; but my invention differs from this very materially, inasmuch as it indicates when, or sounds an alarm for, any irregularity in the running of burrs, whether such irregularity arises from the feed or any other cause or whether the hopper be full or empty; and my invention consists in combining with the spindle or runner-shaft of a mill or with any moving part of the mill that operates directly or indirectly the burr or burrs thereof a governor that will through suitable mechanical appliances sound an alarm or indicate on a scale, or both, when the burr or burrs are running irregularly, whatever may be the cause of such irregularity or variation from the fixed or proper grinding speed of the burr or burrs.

To enable others skilled in the art to make and use my invention, I will proceed to describe the same with reference to the drawings.

a represents a pulley on the burr-spindle

of a mill, and *b* an endless belt passing around it to give motion to the spindle, which motion may come from any first-moving power and be transmitted in any of the well-known ways. On the spindle there may be another pulley *c*, around which and around a pulley *d* on the governor-shaft *A* passes an endless belt *e* for revolving said shaft. Of course gearing may be used for producing and transmitting these motions, instead of belts and pulleys.

Near the top of the shaft *A* there is fixed a cross-head *B*, that turns with the shaft *A*, and to this cross-head is attached the arms *C* and balls *D* by pivots or hinges upon which they may swing as the motion of said shaft diminishes or increases.

E is another cross-head, made fast to a sleeve or boss *F*, that can move up or down on the shaft *A*, and the arms *C* are connected to this cross-head *E* by the connecting rods or bars *G* which form the governor.

On the sleeve or boss *F* there may be two cams *f g*, the former *f* having but one beat or throw 1 and the latter two or more throws or beats 2 2, for a purpose to be presently described. On the sleeve *F* there may be, also, a rod or indicator *h*, that will rise and fall with it, and thus mark on a scale *i* whether the burr or burrs are running at the speed desired for good grinding, or whether they are running faster or slower than that speed. On the shaft *j*, which is pivoted at top and bottom, so as to turn on its journals or bearings, but restrained from turning too freely by a spring *k*, there is an arm *l*, which when the cams *f g* are at a certain point or position (and which should be indicative of the proper speed of the burr or burrs of the mill) will not come in contact with them; but if from any cause the speed of the mill should become reduced the governor of course will show it and the balls *D* will drop, letting down the sleeve or boss *F* and bringing the cam *f* so that it will strike the arm *l* and cause said arm or a prolongation of it to strike a bell *m*, each rotation of the cam striking one blow, and thus notifying the attendant that the burr or burrs are running too slow. If the speed of the mill should become excessive, the governor will raise up the sleeve or boss *F*, and consequently the cam *g*, bringing it into a position where

it will strike the arm *l* and cause said arm in a similar manner to strike the bell, though the cam *g*, having two beats, will cause double the number of strokes on the bell than the other cam *f* would do, thus indicating to the attendant by the rapidity of the sound that the mill is running too fast. A second bell *n* may be used, if found desirable. It is hung to an arm *o*, that is connected to the arm *l* by a rod *p*, so that it may be rung from the motion of the arm *l*.

In practice the indicator *h* should be near the spout where the flour passes from the burrs, as the attendant there would have an opportunity to see it oftener, though it may be placed elsewhere in any convenient position. So, too, of the bell or bells. They may be placed in any part of the mill where the attendant would be most likely to be, and so that he may attend to the alarm.

The shaft *A* may be made hollow, and a spindle *r* may be passed down through it, and by means of slots *s* through said hollow shaft this spindle may be connected to the sleeve or boss *F* and rise and fall with said boss or with the cross-head *E*, and upon the top of this spindle, which may extend up into any of the upper stories of the mill, may be two cams *f' g'*, which will in a similar manner, as heretofore described of the cams *f g*, cause an arm *l'* to strike a bell *m'* with greater or less rapidity and indicating by the sound that the mill is running too slow or too fast. Thus one, two, or more alarms may be sounded notifying the attendant that his services are required. He may, too, without any alarm being given, note by the indicator whether it stands at the true point fixed for it when the speed is proper for good grinding or whether it indicates that the speed is slightly increasing or diminishing from the proper speed, and thus before an alarm is given he may be able to anticipate it and regulate the power or the feed or the burrs, as the case may be, to prevent the diminished or increased speed.

Instead of a single arm *l l'* for striking or ringing the bell, a double one *l l'*—such as shown in Fig. 3—may be used, the arms being wide enough apart to allow one or the other of the cams *f g* or *f' g'* to revolve between them without touching either when the proper speed is on, but bring them in action by the raising or lowering of the cams when the speed is improper, and instead of the governor shown in Fig. 1 a more simple arrange-

ment such as is shown in Fig. 2—may be used. In this construction but a single arm *C'* and a single ball *D'* are used on the shaft *A'*. The sleeve *F'* in this case, as well as the cams *t u*, are all made in one and the same piece with the arm and ball, and they are pivoted to the shaft *A'* at *v*. Now, when this ball is in a position that the desired speed of the mill is set for or will produce, then the cams *t u* would revolve without striking the arms of the bell lever or arm; but if this speed should be changed for a faster one or a slower one either it will throw into action one or the other of the cams by tipping them on the shaft or spindle and thus bring one or the other into contact with the bell-arm and sound the alarm, as the case may be, the difference in the strokes upon the bell indicating what the mill requires to keep its speed at a regulated velocity. It is not of course necessary that all these alarms should be used on one mill or pair of burrs, one of them in ordinary cases being sufficient. I have shown the different methods that I have or can employ to effect the purpose and may use one, two, or more of them, as may be deemed essential. Nor do I confine my invention to the driving of the governor from the burr-spindle, as it may be worked from any other moving part of the mill-gearing equally as well.

Having thus fully described the nature and object of my invention, what I claim therein as new, and desire to secure by Letters Patent, is—

1. Combining with the burr-spindle of a mill or with any other moving part of the mill-gearing a governor and an alarm apparatus by which any variation from the proper or previously-regulated velocity of the burr or burrs for good grinding will be brought to the notice of the attendant, substantially as described.

2. In combination with the burr-spindle or other moving part of the mill-gearing and a governor, a rod, hand, or indicator that will show to the attendant when the speed of the burr or burrs is at its regulated or desired velocity or any variation therefrom, whether greater or less, substantially as described.

EDWIN CLARK.
